UNITED STATES PATENT OFFICE.

GERALD R. LIVERGOOD, OF HOUSTON, TEXAS.

PIPE-ENGAGING SLIP.

Application filed July 29, 1921. Serial No. 488,312.

To all whom it may concern:

Be it known that I, GERALD R. LIVERGOOD, a citizen of the United States, residing at Houston, Harris County, Texas, have invented a certain new and useful Improvement 5 in Pipe-Engaging Slips, of which the following is a full, clear, and exact description, such as will enable others skilled in the art to which it appertains to make and use the same.

My invention relates to pipe-engaging slips for use particularly in drilling operations.

During the process of drilling for oil, water, gas, etc., it is necessary to frequently remove the drill stem and drill from the well to repair the drill and also to replenish the lubricant. The drill stem is unscrewed in lengths of several sections of 15 pipe at a time, during the removal operation, and, while the unscrewing is proceeding, the drill-stem is supported in the rotary by means of slips. The rotary has a downwardly tapered seat in its upper end and the 20 slips comprise sector shaped jaws toothed on their inner faces and shaped to fit the drill stem. On their outer faces the said slips are tapered downwardly to fit the seat in the rotary. The difficulty most commonly 25 experienced with the usual type of slip is that it jams in the rotary and cannot be easily removed.

An object of my invention is to provide a 30 pipe engaging slip that is made up of a plurality of jaws assembled together as units in such manner as to allow free lateral and vertical play of the separate jaws and hence permit the quick release of the slips from the rotary and the pipe.

Another object is to provide a slip that is 35 light in weight and yet strong in construction and capable of withstanding the heavy duty to which such slips are subjected.

Another object is to provide a slip for 40 rotary which is made up of a plurality of jaws mounted on a specially constructed cage or frame designed in such manner as to permit of the quick assembly of the separate jaws thereon.

Other objects and advantages will clearly 45 appear, to one skilled in the art, from the description which follows.

In the drawing, Fig. 1 is a top plan view 50 of a set of slips placed in position to receive the pipe. Fig. 2 is a transverse sec-

tion through one of my assembled slips taken along the upper supporting rod. Fig. 3 is a perspective view of one of the jaws showing the supporting rods in section. Fig. 4 is a perspective view of the assembled frame upon which the jaws may be mounted. Figs. 5 and 6 are front and side elevational views respectively of one of the spacing yokes, and Fig. 7 is a transverse section on the plane 7—7 of Fig. 6.

The present invention is designed as an improvement on the design of slip set forth in my prior Patent No. 1,381,074, granted June 7, 1921. This embodiment is particularly adapted for the larger sizes of pipes 60 and for heavy loads. The jaws must be made of small enough sectors to not grip the pipe over a large enough area to jam against the pipe and lock and also to be free to move in all directions relative to the supporting 65 cage and to each other. To construct the separate jaws so that they will be strong and also light in weight, I form them as shown in Fig. 3. Each jaw 1 is sector shaped, the inner gripping face being 70 toothed at 2. The sides of the jaw are recessed so as to dispense with some of the weight of the jaws. The jaws will then be in central transverse section approximately 75 like a curved I-beam, as shown in Fig. 2.

In mounting these jaws for handling, I 80 assemble a plurality, preferably four, upon a supporting cage in such manner that they may be operated as a unit. For this purpose I provide a cage or frame shown separately 85 in Fig. 4. It comprises upper and lower curved bolts or rods 3 and 4, respectively. These rods,—one of which is best shown in Fig. 2—are formed with a central enlarged 90 portion 5 having shoulders 6, 6 at points 95 spaced a suitable distance from the center. Beyond the shoulder 6 the rod is reduced slightly in diameter at 8 for a short space and is then again reduced abruptly in diameter at 9 to provide a second shoulder 7. 100 From this shoulder to the outer end of the curved rod 3 the diameter remains the same. The rods are threaded at each end to receive a nut 10 which is castellated to receive a cotter pin, or other suitable means, passing through the slots in said nut and through a transverse opening 11 in the rod to lock the nut against removal.

To receive the transverse rods 3 and 4, the 105 jaws are provided with two openings 12 110

intermediate the ends thereof, these openings being somewhat oblong and of somewhat greater length in vertical than horizontal diameter. They are of such size as 5 to receive the rod very loosely therein so as to allow the movement of the jaws in all directions relative to the supporting rod. The openings 12 are bored only in the central web 13 of the jaws, the intervening 10 space between the webs forming a housing for a spacing means to hold the adjacent jaws loosely apart.

The spacing means comprises a washer 14 bearing against the shoulder 6 and of such 15 diameter as to prevent its movement through the opening 12 in the jaw. The washer 15, bears against the shoulder 7 on the other side of the web of the jaw, and prevents movement beyond that point in the opposite 20 direction. Thus it will be seen that the jaw whose web 13 comes between said washers will have a limited lateral movement in each direction, but is held approximately in position relative to the other jaws. At the 25 outermost end of each rod in each separate slip, the nut 10 will prevent the movement of the outer jaw beyond a certain point. Bearing against the inner face of the nut 10 is a spacing sleeve 16 serving to space 30 away from the nut 10 a washer 17.

Between the washer 17 and the washer 15 is a spacing post 18. This acts to space the two said washers apart and to hold them rigidly in position.

35 The construction of the spacing posts 18 is shown best in Figs. 4, 5 and 6. Each post comprises an upright member 19 having upper and lower sleeves 20 and 21 respectively, to support the rods and through which the 40 said rods are adapted to pass. These sleeves have openings 23 therein to receive the rods. The upper end of each of the spacing posts 19 is extended upwardly at 24 to furnish an attaching means for a handle. For this 45 purpose the upper extension 24 is recessed centrally, as shown at 25. This recess is of such diameter as to receive a cable or other similar means 26 therein and to allow space outside thereof to receive some soldering 50 means 27; this means may be lead, Babbitt, or other suitable metal. The supporting rods 3 and 4 are held rigidly apart in spaced 55 position by means of these spacing posts, but the jaws are fitted so loosely upon the said rods that they move both vertically and laterally relative to the frame or cage thus constructed, and each jaw will also have 60 separate play relative to the adjacent jaw.

As will be noted, the spacing posts 19 are fitted within the recesses provided in the sides of the jaws. To allow space for the upward extension 24 on each of the posts, however, it is necessary to form semi-cylindrical lateral grooves or notches 28 in the 65 adjacent upper ends of the said jaws. These

notches are of a diameter somewhat larger than the posts 19, thus allowing the jaws to move freely upon the frame. The handle made up of the cable 26 extends upwardly from the ends of the posts, and serves to connect the two adjacent posts on each slip. The cable is provided with a short length of pipe 29 through which it passes, said pipe furnishing a hand hold for the driller. 70

On the upper end of each of the jaws 1 75 I prefer to form a central upstanding lug 30. With a lug such as this on each adjacent jaw it will be noted that the cable 26 forming the handle will be shielded somewhat between the two adjacent lugs 30 so that 80 weights striking against the upper ends of the slips will not be apt to mash or break the cable so as to damage same. In this way a handle made in this manner will last for a long period of time without breaking. 85

The operation of my pipe engaging slip will now be clear without further description. The slips comprising each set, of which there will be two or more, will be secured together by the frame or cage constructed as 90 described, and may be moved to and from their seat in the rotary as a unit. Being constructed with a toothed face of narrow width it will not act to jam against the pipe. The jaws will therefore bear against the pipe 95 on all sides with practically equal pressure. Each of the separate jaws will be allowed movement upon the supporting rods 3 and 4 in vertical and lateral directions due to the size of the openings 12 through which the 100 rods pass, and to the space provided between the adjacent shoulders formed upon the supporting rods in the manner described. This lateral play will allow them to be fitted easily about the pipe and within the rotary 105 seat and will allow each jaw to move so that it will quickly release when the slip is raised by means of its handle.

Slips constructed in accordance with this design are capable of withstanding heavy 110 loads and will not break or mutilate under the rough usage to which such slips are commonly subjected. Recessing the sides of the jaws as shown will make them light in weight so that they may be easily moved 115 by the driller.

Having thus described my invention, the further objects and advantages of which will be apparent to one skilled in art, what I claim as new and desire to protect by Letters Patent is:

1. In a pipe engaging slip, a plurality of separate clamping jaws mounted upon a frame comprising upper and lower supporting rods extending laterally through each of 125 said jaws, upright spacing posts adjacent each of the ends of said rods, said posts having openings to receive said rods, handles secured to said posts and means on said rods to retain said jaws loosely thereon. 130

2. In a pipe engaging slip, a plurality of separate clamping jaws mounted upon a frame comprising upper and lower supporting rods extending laterally through each of said jaws, an upright spacing post having openings therethrough to receive said rods, and means on said rods to retain said jaws loosely thereon. 40
3. In a pipe engaging slip, a plurality of arcuate pipe engaging jaws having upper and lower transverse openings therethrough, rods passing loosely through said openings, means intermediate the ends of said jaws to space the said rods rigidly apart, and means 50 to retain said jaws on said rods.
4. In a pipe engaging slip, a plurality of arcuate pipe engaging jaws having transverse openings therethrough intermediate their ends, rods fitting loosely in said openings, means to secure said jaws loosely on said rods and means to move said slip as a unit. 55
5. In a pipe engaging slip, a plurality of arcuate pipe engaging jaws, the sides of said jaws being recessed to provide a web having upper and lower transverse openings, supporting rods extending loosely through said openings, spacing posts in said recesses and having openings to receive said rods and 60 means to retain said jaws loosely on said rods.
6. In a pipe engaging slip, a plurality of pipe engaging jaws, the sides of said jaws being recessed to provide a central upright 65 web having openings therein, transverse rods of smaller diameter than said opening extending therethrough, means to retain said jaws on said rods and means housed in the
- recessed sides of said jaws to space said rods rigidly apart. 40
7. In a pipe engaging slip, a plurality of pipe engaging jaws, means positioned intermediate the ends of said jaws to retain said jaws loosely together and means secured to said retaining means to move said jaws as a 45 unit.
8. In a pipe engaging slip, a plurality of pipe engaging jaws, rods passing transversely through said jaws intermediate the ends of said jaws, and means to space said 50 rods rigidly apart.
9. In a pipe engaging slip, a plurality of arcuate jaws recessed on the side thereof, said jaws having transverse openings therethrough, a supporting rod passing loosely 55 through said openings, means to retain said jaws loosely on said rod and means to move said slip.
10. In a pipe engaging slip, a plurality of pipe engaging jaws, a rod passing transversely through said jaws intermediate the ends thereof, means to retain said jaws loosely on said rod and means to move said jaws as a unit. 60
11. A pipe engaging means composed of a plurality of separate slips, each slip comprising a plurality of pipe engaging jaws, means intermediate the ends of said jaws and fitted loosely therein, to hold said jaws together as a unit, and means to move each of 65 said slips.

In testimony whereof, I hereunto affix my signature, this the 26th day of July, A. D. 1921.

GERALD R. LIVERGOOD.
